UNITED STATES PATENT OFFICE.

JASPER N. YELTON, OF CATAWBA, KENTUCKY.

BURGLAR-ALARM.

SPECIFICATION forming part of Letters Patent No. 339,962, dated April 13, 1886.

Application filed February 9, 1886. Serial No. 191,317. (No model.)

To all whom it may concern:

Be it known that I, JASPER N. YELTON, a citizen of the United States, residing at Catawba, in the county of Pendleton and State of Kentucky, have invented certain new and useful Improvements in Burglar-Alarms, of which the following is a specification, reference being had therein to the accompanying drawings.

10 This invention relates to certain improvements in burglar-alarms, its object being to provide a device of simple and effective construction that will be applicable to the doors and windows of buildings, and be so arranged that upon opening the door or window to which it is applied an explosion will occur, and thus signify the presence of burglars and alarm the occupants of the building; and the invention consists in certain novel features of 15 construction and arrangement of parts, as will be more fully hereinafter described, and particularly pointed out in the claim.

In the drawings annexed, Figure 1 is a perspective view, showing the application to a 20 door, of a signaling device embodying the features of my improvement. Fig. 2 is a perspective representation of my improvement, showing its application to use in connection with a window. Fig. 3 is a sectional view of 25 the alarm mechanism.

A is a door; B, the door-frame.

C C' is a bracket having its part C' perforated for the reception of screws, by means of which it is secured to the door-frame. The 30 part C is provided with a longitudinal recess for the reception of a bow-shaped spring, D, and at its outer end with a recess, F, for the reception of a blank cartridge or other explosive.

35 E E' is a hammer pivoted to the bracket C, as shown at d, in a manner to engage the spring D, and is provided at its impact end with a point, d', for effectively engaging with the cartridge.

40 G G' is a door-bolt and socket-plate of ordinary construction. By setting the sliding bolt G in the position shown the hammer will be set by closing the door either from the inside or outside of the building. Should

the door or window be opened while the 50 device is set for action, the bolt will strike the portion of the hammer marked E and cause the same to explode the cartridge in the recess F. By adjusting the bolt G so it cannot engage with the hammer, the mechanism 55 will be made inactive and the door or window may be opened or closed without producing the effects described.

Referring to Fig. 2, K and K' represent the outside and inside sashes of a window. The 60 bracket C C' is secured to the sash K in a vertical position, as shown.

H is an arm affixed to or made integral with a disk-like body, H', provided centrally with a vertical perforation for the reception 65 of a bolt, h, which pivotally secures the same to a plate, H'', affixed to the sash K' by screws or other suitable means.

H' is a handle secured to the disk for the purpose of operating the same. 70

It is evident that instead of the device attached to the inside sash, K', any of the well-known sash-locks may be used. The center of the bow-spring bears against the straight side of the arm E of the hammer, so as to 75 force the hammer downward when tripped, and against the flat side of the arm E, so as to hold said hammer-lever in an elevated position until tripped, and then permit it to be forced down upon the cartridge, so as to explode the same. It will be seen that the hammer-lever is pivoted directly over the crown of the bow-spring, so that the angle in shifting below the pivotal point permits the single spring to hold and move the lever 80 in the opposite direction, as required. By grasping and holding the hammer while the bolt G or arm H are being adjusted to clear the same, it may be set in the position shown in Fig. 3, and the door or window opened 85 without exploding the cartridge, as occasion may require; but this adjustment of course can only be made from the inside.

Having explained the features of my improvement, what I claim as new, and desire 90 to secure by Letters Patent, is—

In a burglar-alarm, a bracket provided with a longitudinal recess for the reception

of a bow-spring and a recess for the reception of a cartridge, and an angular lever or hammer pivoted in said longitudinal recess directly over the crown of the bow-spring, so as to be operated upon by the same and explode the cartridge, in combination with an adjustable operating-bolt, substantially as described.

In testimony whereof I affix my signature in presence of two witnesses.

JASPER N. YELTON.
